ROBERT A. HALL, OF NEW YORK, N. Y., ASSIGNOR TO STANDARD STOPPER COMPANY, OF NEW YORK, N. Y., A CORPORATION OF NEW JERSEY.

CAP FOR RECEPTACLES.

No. 826,244.

Specification of Letters Patent.

Patented July 17, 1906.

Application filed October 28, 1904. Serial No. 230,320.

To all whom it may concern:

Be it known that I, ROBERT A. HALL, a citizen of the United States, residing at New York, county of New York, and State of New York, have invented certain new and useful Improvements in Caps for Receptacles, fully described and represented in the following specification and the accompanying drawings, forming a part of the same.

10 This invention relates to certain improvements in capped receptacles, and more particularly to that class of capped receptacles in which a cap having a circumferentially-continuous flange is attached to a receptacle 15 by bending the flange or a certain portion thereof beneath a locking-shoulder on the receptacle.

It is old in the art of capping receptacles to close a receptacle by employing a cap having 20 a continuous flange and bending the flange into locking contact with the under side of a shoulder on the receptacle, the bending operation being effected either by a spinning or by a pinching or compressing tool. In these 25 constructions the shoulder of the receptacle at or about the line of the greatest diameter of the locking-shoulder serves as a fulcrum across which the flange is bent. Such bending, even where it is progressive bending of 30 the character known as "spinning," subjects the receptacle to more or less strain, so that there is liability of breakage, especially if the caps be made of comparatively heavy metal. Furthermore, where the metal of the con- 35 tinuous flange bends across some part of the locking-shoulder as a fulcrum it is very difficult to give the metal a permanent set of such a character as to cause the bent portion to lie snugly against the under side of the 40 locking-shoulder and at the same time produce such a joint between the cap and the receptacle as will enable the cap to be readily removed when desired. If, for instance, the metal be lightly bent or spun across the 45 greatest circumference of the locking-shoulder and against the under side thereof, the metal after the pressure of the spinning or bending tool is removed springs away from the shoulder of the receptacle. While the 50 amount of this spring is very small, it is still sufficient to prevent in many cases the for-

mation of a reliable seal, especially where the contents of the receptacle is a liquid under pressure.

Caps have been made the continuous 55 flanges of which have special features of construction—as, for instance, corrugations—the function of which was to make the flange readily contractible and to render unnecessary in the formation of the seal to bring the 60 flange in close contact with the locking-shoulder on the receptacle at all points, it being sufficient to form a seal with this class of caps if the shoulder of the receptacle is embedded in the crests of the corrugations. The 65 corrugations, which have been practically employed, however, stiffen the flange of the cap vertically and make it necessary to employ very heavy pressure in sealing receptacles, which where the receptacles are of glass 70 is liable to produce considerable breakage. Furthermore, these caps require special tools in their construction, and considerable expense is involved in their manufacture. It has also been proposed to provide a cap hav- 75 ing a continuous flange with a circumferential bead the purpose of which was to sustain the impact of the applying-tool and reduce the liability of breakage. This form of cap is open to the objection that the bending of 80 the flange into locking position must take place substantially across the line of greatest diameter of the locking-shoulder. The flange of the cap, however, is so stiffened by the bead formed therein that great pressure is 85 necessary in order to lock the cap in position, and difficulty is experienced in applying this form of cap so as to make a hermetic seal. This form of cap has not, therefore, gone into practical use.

It is one of the objects of this invention to produce a capped receptacle the cap element of which shall consist of a cap having a continuous flange, the cap being applied to a receptacle having a locking-shoulder in such 95 a way that the point at which the bending of the flange in the applying operation takes place is out of contact with the shoulder on the bottle, so that the shoulder does not support or act as a fulcrum for the cap-flange.

A further object of the invention is to produce a capped receptacle the cap element of

which shall be simple in construction, and therefore capable of being cheaply made by simple tools and being of such a character that a proportionately-large number of caps can be obtained from a given amount of material, the receptacle being of such a construction that the cap and receptacle may be readily united by mechanism which is simple in construction and when united forming an efficient closure which may be readily broken when it is desired to remove the cap from the receptacle.

With these and other objects not specifically stated in view the invention consists in certain constructions and combinations hereinafter pointed out.

Referring to the drawings, Figure 1 is a sectional elevation of a cap prior to its application to the receptacle, and Figs. 2 and 3 illustrate in sectional elevation capped receptacles embodying the invention.

The caps which are to be used in carrying out the invention may be constructed of various materials. A material well adapted for the caps is turned sheet-iron, this material being known in the trade as "tin."

The cap will consist of a top or crown having a flange depending therefrom, this flange being circumferentially continuous, at least so far as its lower edge is concerned. The configuration of the cap may be considerably varied. A preferred form of cap is shown in Fig. 1, said cap having a crown 1, from which depends the flange 2. The lower part of the flange will preferably be flared outward, as shown at 3. When it is desired to make a hermetic seal between the cap and the receptacle to which it is to be applied, a gasket or sealing-ring of any suitable form or material may be employed. In the construction shown a cork disk 4 is shown in position in the interior of the cap.

The cap may be used in connection with receptacles which may be made of any suitable material; but such receptacles will be provided with a locking-shoulder. In the particular construction selected to illustrate the invention a bottle-top is shown, said top being marked 5 and the locking-shoulder thereon 6.

In applying the cap to a receptacle the lower edge of the flange is bent inward, the cap being at this time held upon the bottle by any suitable means. The inward bending of the cap-flange will be effected by applying pressure by means of a suitable tool to the edge of the flange. While any suitable tool may be employed for this purpose, a grooved wheel produces satisfactory results. However the pressure is produced, it will be of such a character as to cause the part 3 to turn inward and travel toward the under side of the shoulder of the receptacle. This

bending of the flange takes place at a point which is out of contact with the shoulder of the receptacle, so that when the cap is in locked relation the bend or curve in the flange, this part being marked 7, which connects what may be termed the "unbent" part of the flange 2 and the "bent" part of the flange (see Figs. 2 and 3) lies out of contact with the shoulder of the receptacle.

The locking of the cap in position is effected by causing the inner side of the bent part 3 (see Figs. 2 and 3)—that is, the side which lies next the unbent part 2—to bear against the under side of the locking-shoulder. In applying the cap the bending operation may be stopped as soon as or practically as soon as the extreme edge of the bent part strikes the shoulder of the bottle, so that only a comparatively small portion of the inner side of the bent part lies against the bottle-shoulder, this being the construction illustrated in Fig. 2, or the bending may be continued until the upper edge is given a reverse bend, as illustrated in Fig. 3. The seal produced by carrying the bending forward, as illustrated in Fig. 3, will be usually found to be the most effective, as the carrying forward of the bending more reliably compensates for irregularities in the height of the locking-shoulders, which irregularities are particularly common in receptacles formed of glass or vitreous material.

The cap employed in carrying out the invention for ordinary purposes can be made of very light material and can be very economically produced, it being only necessary to cut circular disks from sheets of material and subject them to a drawing operation in a die of very simple form. Furthermore, a comparatively small area of metal is required for making the caps, so that a comparatively large number of them can be obtained from a given quantity of material. The caps are therefore cheap to manufacture. Inasmuch, furthermore, as very little strain is set up on the receptacle in the act of applying a cap, the liability of breakage is reduced to a minimum, and the applying mechanism may be exceedingly simple in its character and rapid in its operation.

What is claimed is—

1. The combination with a receptacle having a locking-shoulder located exteriorly with respect to the mouth thereof, of a cap having the lower part of its flange circumferentially continuous and bent inward, the inner surface of said bent part being in locking contact with the shoulder and the bend in the flange which joins the bent and unbent parts lying out of contact with the shoulder, substantially as described.

2. The combination with a receptacle having a locking-shoulder located exteriorly

with respect to the mouth thereof, of a cap having the lower part of its flange circumferentially continuous and bent inward and upward, the inner surface of said bent part being in locking contact with the shoulder and the bend in the flange which joins the bent and unbent parts lying out of contact with the shoulder, substantially as described.

In testimony whereof I have hereunto set my hand in the presence of two subscribing witnesses.

ROBERT A. HALL.
